CLAIM

The ornamental design for an air intake assembly of a motorcycle fairing, as shown and described.

DESCRIPTION

FIG. 1 is a front elevational view of an air intake assembly of a motorcycle fairing showing our new design;

FIG. 2 is a left side elevational view thereof;

FIG. 3 is a right side elevational view thereof;

FIG. 4 is a top plan view thereof; and,

FIG. 5 is an enlarged section view taken along line 5—5 in FIG. 1.

The broken line showing of the environment forms no part of the claimed design.
